UNITED STATES PATENT OFFICE.

DAVID W. JONES, OF CHICAGO, ILLINOIS, AND WILLIAM J. MILLER, OF COLUMBUS, OHIO, ASSIGNORS OF ONE-THIRD TO JULIUS F. STONE, OF COLUMBUS, OHIO.

ROTARY VALVE FOR INTERNAL-COMBUSTION MOTORS.

1,261,941.

Specification of Letters Patent.

Patented Apr. 9, 1918.

Application filed June 10, 1914. Serial No. 844,175.

To all whom it may concern:

Be it known that we, DAVID W. JONES and WILLIAM J. MILLER, citizens of the United States, residing at Chicago, in the county 5 of Cook and State of Illinois, and in Columbus, county of Franklin, and State of Ohio, respectively, have invented a certain new and useful Improvement in Rotary Valves for Internal-Combustion Motors, of which the following is a description, reference being had to the accompanying drawings, which form a part of our specification.

Our invention relates to a rotary or disk valve for internal combustion motors, having for its object the provision of a valve whereby greater or increased efficiency will be had, namely more horse power be delivered with a given sized motor by reason of the positive action of the valve.

20 A further object of the invention is the provision of a construction whereby a more economical motor will be produced from the standpoint of manufacture, because of the fact that a single valve or member is adapted 25 to serve a plurality of cylinders, controlling both the intake or supply and the exhaust of the gases, with the result that a better shaped combustion space in the cylinders will be had by reason of the fact that a single port need only be provided to serve both 30 as the inlet and the exhaust port.

In addition to the elimination of the parts by reason of the employment of our invention, the invention also results in the elimination 35 of the mechanical noises heretofore encountered with valves as at present in use due to the multiplicity of parts and the tendency or likelihood of the respective parts becoming loose or worn, as well as the elimination 40 of the resultant noises due to the operation or movement of the various parts.

In addition to the foregoing advantages, the invention possesses other advantages inherent in the construction, which will be 45 fully apparent from the following detailed description.

In the drawings:

Figure 1 is an end elevation of a motor provided with our improved valve.

50 Fig. 2 is a side elevation thereof.

Fig. 3 is a sectional view taken on the line 3—3 of Fig. 1, looking toward the cylinder, namely, in the direction of the arrows, with the valve removed from its casing.

Fig. 4 is a top plan and partial sectional view on the line 4—4 of Fig. 2.

Fig. 5 is a sectional view taken on the line 5—5 of Fig. 3 and looking in the direction of the arrows.

Fig. 6 is a sectional view taken on the line 6—6 of Fig. 3, looking in the direction of the arrows.

Fig. 7 is an end elevation of our improved valve removed from its casing.

Fig. 8 is a vertical sectional view taken on the line 8—8 of Fig. 7, looking in the direction of the arrows.

Fig. 9 is a sectional view taken on the line 9—9 of Fig. 8, looking in the direction of the arrows.

Figs. 10, 11, 12, and 13 are diagrammatic views representing a two-cylindered motor provided with our improved valve illustrating the relative positions of the valve and port of a four-cycle motor; Fig. 10 illustrating the valve in position to permit one of the cylinders to exhaust while the second cylinder is being supplied or namely at the suction stroke; Fig. 11 illustrating the valve in such position that the first mentioned cylinder is being supplied or namely is at the suction stroke, while the second mentioned cylinder is at the compression stroke; Fig. 12 illustrating the valve in such position that the first mentioned cylinder is at the compression stroke while the second mentioned cylinder is at the point of ignition; while Fig. 13 illustrates the valve in position so that the first mentioned cylinder is at ignition point and the second mentioned cylinder is at the exhaust point or cycle.

In the particular exemplification of our invention, as illustrated in the drawings, our improved valve is shown applied to a two-cylindered motor, with the ports of the cylinders spaced ninety degrees apart, and the valve so geared to the crank-shaft of the motor that the valve will make one revolution to two revolutions of the crank-shaft. It will be understood, however, that the invention may be applied to a motor provided with a multiple of cylinders, and that the ports of the respective cylinders may be consecutively spaced apart, as for example, say forty-five degrees, in which instance the valve may be so geared to the crank-shaft as to make one revolution to four revolutions of the crank-shaft; it being under-

stood that any spacing of the ports may be had suitable for the proper sized openings whereby the desired result will be secured.

In the illustration of the adaptation of our invention, the pistons of the two cylinders of the motor are preferably shown at half stroke in Figs. 1 and 2; the cylinders being illustrated at 15 and 16, see Figs. 1, 2, and 4, and the bore of the cylinders being illustrated in dotted lines, while the piston-heads 17 and 18 of cylinders 15 and 16, respectively, are also shown in dotted lines, see Fig. 2. The pistons are provided with the usual pitmen illustrated at 19 and 20, respectively, which are also shown in dotted lines and extend into the crank-casing 21; the pitmen 19 and 20, being connected with the usual cranks shown in dotted lines at 22 and 23, respectively, which are secured to the crank-shaft 24.

Secured to the crank-shaft 24, preferably to the outside of the crank-casing 21, is a sprocket-wheel 25 provided with sprocket-chain 26, whereby sprocket 27 is rotated; sprocket 27 being keyed or otherwise secured to worm-shaft 28. The worm-shaft 28 has suitable bearing, as for example in bracket 29, on the motor and in the lower portion of the valve-casing 30, which is secured to the motor casting or cylinder portion, being preferably formed integral therewith as shown. The casing or housing 30 is formed to provide a circular chamber and is preferably shown provided with a suitable number of lobes or bosses at 31, provided with threaded holes or sockets to receive the bolts 32 whereby the casing-cover 33 is removably secured in place; the bosses or lobes being more clearly shown in Fig. 2 while the cover and retaining bolts are clearly shown in Fig. 1.

The casing member or cover 33 is provided with a centrally disposed boss or portion 33^a, which is elongated to constitute a gas-port and is adapted to receive the usual carbureter indicated at 34, Fig. 1; the carbureter 34 being secured to the port 33^a in any suitable manner as, for example, by the short pipe or tubing 35 shown in Fig. 1, which may be screwed onto the carbureter and suitably secured to the elongated port 33^a of the casing-member or cover 33. The valve-casing or chamber preferably composed of the portions 30 and 33, is bored or channelled to receive the end of the worm-shaft 28; the construction of the casing in this respect being very clearly shown in Figs. 3 and 5, wherein the valve and the worm-shaft are removed in order to more clearly illustrate the construction of the casing interior or chamber, as well as its relation to the ports 36 and 37 of the cylinders 15 and 16, respectively.

The mixture or gas-controlling valve consists of a disk or circular member 38, pref-

erably shown as an integral member or casting, the outer periphery or circumference whereof is provided with gearing or teeth 38^a, formed so as to mesh with worm-shaft 28.

The interior of the valve 38 is intended to be divided into separate portions or chambers, preferably by means of the irregularly formed partition or wall 39, see Fig. 8, whereby the major portion of the interior of valve 38 constitutes a gas supply or inlet chamber, indicated at 40 in Fig. 8.

The one side wall of the valve is provided with the hub portion 41 which is adapted to have bearing in the boss or portion 33^a of cover member 33, see Fig. 5, and the hub 41 is provided with an opening or port which constitutes the gas inlet 42, as clearly shown in Fig. 9; the opening 42 being in register with the opening or port extending through the elongated portion 33^a, and, therefore, receives the gaseous mixture from the carbureter 34. The port 42 admits the gas to the chamber 40, which latter is provided with a port 43 extending through one side of the valve so as to supply the cylinders with the gaseous mixture when the valve 38 is rotated sufficiently to bring port 43 into register with the port of the cylinder, indicated at 37 in Fig. 5. The other chamber 44 formed by the irregular partition or wall 39 constitutes a discharge passage or port 44 which extends transversely through the valve 38; the chamber or port being open at both sides of the valve, as very clearly shown in Fig. 9. The ports 43 and 44 are spaced at a predetermined distance apart, as previously stated; the spacing or distance being determined by the speed of rotation of the valve relative to the speed of rotation of the crank-shaft; the spacing in the particular exemplification shown in the drawings being a distance of ninety degrees, as clearly shown.

In the preferred construction, the ports in the valve, namely ports 43 and 44, are preferably elongated, and the ends of the ports, forwardly presented in the movement of the valve relative to the ports in the cylinders, are preferably substantially semi-circular as very clearly shown in Fig. 8 and in dotted lines in Figs. 10 to 13, inclusive, in order that a wider area or full opening will be presented at the initial opening of the ports and thus permit of a free and rapid flow of the gases.

The side of the valve opposite to the side described as provided with the inlet opening 42, is provided with a boss or hub 45, which has bearing in the socket 46 formed in the valve-casing or chamber as very clearly shown in Fig. 5. It is evident, therefore, that the valve 38 will be provided with proper bearings to permit of its rotation when the cover member 33 of the valve-casing or chamber has been secured in place,

so that the valve will be retained in proper operative position on the cylinders.

In order that a gas-tight relation may be maintained between the rotating valve 38 and the walls of the cylinders adjacent the ports in the respective cylinders, we provide a packing ring 47, of suitable material fitted in a circumferential socket or groove about the port of each cylinder; as for example in Fig. 6, where port 37 is illustrated in cylinder 16, the packing ring 47 is very clearly illustrated in cross section, being inserted in the circumferential socket or groove 48 in the wall of the cylinder, and the packing ring is maintained against the side wall of the valve 38 by means of springs 49, of any suitable number and construction, whereby a constant gas-tight connection will be effected to prevent the intake and exhaust gases from escaping along the sides of the valve. As the valve 38 fits snugly within the chamber of the valve-casing, it is apparent that the supply gases cannot escape from the chamber in the valve except through the port 43 arranged in one side of the valve when said port is brought to register with the port of the cylinder; the ports of the cylinders being closed by the blank side or wall of the valve 38 when the latter has been rotated so as to move the ports 43 or 44 out of register with the ports in the cylinders.

In the diagrammatic views shown in Figs. 10 to 13, inclusive, we illustrate the relative positions of the valve during the various periods or cycles of a two-cylindered motor. For example, in Fig. 10, the one cylinder is shown at the exhaust period, namely cylinder 15, while the second cylinder, namely cylinder 16, is shown at the suction or intake period; at this stage or period, the discharge port 44 is shown registering with port 36 of cylinder 15 so as to allow the expanded gases to freely exhaust from the cylinder; while the supply port 43 (which extends through but one side wall of the valve 38 and is, therefore, shown in dotted lines in the diagrammatic views) is in register with the port 37 of the cylinder 16; the piston of this cylinder being at the suction stroke.

In order that the gases may exhaust from the cylinder by means of exhaust port 44 in the valve, the cover member 33 of the valve-casing is, of course, provided at suitable points with openings which are provided with a suitable exhaust pipe as shown at 50 in Fig. 1. The exhaust pipe 50 is preferably shown bifurcated so as to have the one bifurcation 50^a communicate with opening 51 in the cover-member 33, while the other bifurcation 50^b, see Fig. 4, communicates with the other opening 52 in cover-member 33.

In Fig. 11, the valve has been advanced or rotated a quarter of a revolution so as to

move the exhaust port 44 out of register with the port 36 of cylinder 15 and, therefore, also out of register with the opening 51 in cover member 33; while the supply port 43 of the valve is brought to register with port 36 so that cylinder 15 is being supplied with the gaseous mixture; the piston of the cylinder, therefore, being at the suction stroke or period. In this condition or position of the valve, it is clearly evident that port 37 in the adjacent cylinder 16 will be shut off by the blank wall of the valve; a gas-tight connection being effected by means of the packing ring 47.

In Fig. 12, the valve has been advanced or rotated still farther, namely another quarter of a revolution, or rather a half revolution beyond the position shown in Fig. 10, so that neither port 43 nor port 44 is in register with the ports of the cylinders; the piston of cylinder 15 being at the compression stroke or period, while the piston of cylinder 16 is at the ignition point or period.

In Fig. 13, we illustrate the valve rotated a fourth of a revolution beyond the point illustrated in Fig. 12, that is three-quarters of a revolution beyond the position shown in Fig. 10, namely so as to bring the exhaust-port 44 of the valve into register with the port 37 of cylinder 16; at which stage the supply-port 43, indicated in dotted lines (being to the lower side of the valve as illustrated in the diagrammatic views) is out of register with any of the ports of the cylinders. In this position of the valve, the piston of cylinder 15 would be at the ignition point or period while the piston of valve 38 is at its exhaust stroke or period.

In the preferred form of the valve the same is illustrated as an integral member or casting, the outer surface or periphery whereof is shown provided with the gearing 38^a, but it is clearly evident that the valve may be a composite member composed of spaced side walls and separate gearing properly secured together so as to provide the construction described; in such modified form, however, it would be necessary to so secure the respective members together that a gas-tight connection would be effected or obtained; for that reason it is preferable to form the valve as illustrated in the drawings and as previously described.

It is evident from the construction shown and described, that one valve is made to serve a number of cylinders and, therefore, the number of parts required, as in motors where separate valves are employed, are greatly reduced, with the result that the mechanical noises encountered with the separate valves will be entirely eliminated.

Furthermore, it is also apparent from the construction shown and described that each cylinder need be supplied with but one port which serves both as an inlet and exhaust

port, with the result that, by reason of our improved construction, the cylinders are provided with a better shaped combustion space, and by reason of the positive action 5 of the valve more horse power will be obtained with a given sized motor than would be the case, for example, with the well known puppet type of valve at present in use.

It is also apparent from the foregoing 10 description and the construction illustrated in the drawings that great economy will be effected in the manufacture of a motor provided with our invention.

We have shown and described what we 15 believe to be the simplest and best form of our invention, but the same may be altered in certain respects without, however, departing from the spirit of our invention; the valve may be arranged so as to serve a 20 greater number of cylinders as is clearly evident from the construction; such modifications may be made to adapt the invention to such conditions without, however, departing from the spirit of our invention, 25 and we do not wish to be understood, therefore, as limiting ourselves to the exact construction shown and described.

What we claim is:

30 A rotary valve for internal combustion motors, comprising a casing provided with a removable cover, the cover being provided with a concentric tubular extension and an opening arranged intermediate of the tubular extension and the outer perimeter of the 35 cover, a chambered disk, the sides whereof are provided with axially disposed trunnions, one of said trunnions extending into the tubular extension of the casing and provided with an opening extending there-

through to constitute an inlet for the chamber within the disk, while the opposite side wall at a point adjacent the periphery of the disk is provided with an outlet opening from 40 said chamber, the forward end of said outlet opening, relative to the direction of movement of the valve, being made arcuate to conform with the ports of a cylinder, said disk being provided with an opening extending transversely and directly therethrough 45 at a point adjacent the periphery of the disk and in circumferential alinement with said outlet opening, the side walls of the disk being united by an integral rib or partition disposed about the opening extending transversely through the disk so as to close off 50 communication with the chamber within the disk, the forward end of said partition and the opening, relative to the direction of rotation of the disk, being made arcuate to conform with the ports of the cylinder and 55 adapted to constitute an exhaust opening, the periphery of the disk being formed in the nature of a gear, in combination with a worm shaft meshing with the toothed periphery of the disk, the worm shaft being 60 adapted to be rotated at a predetermined speed relative to the speed of rotation of the crank shaft.
